UNITED STATES PATENT OFFICE

HENRY L. PITMAN, OF WESTFIELD, NEW JERSEY, ASSIGNOR, BY MESNE ASSIGNMENTS, TO ELLIOTT-FISHER COMPANY, OF NEW YORK, N. Y., A CORPORATION OF DELAWARE

COMBINED TYPEWRITING AND COMPUTING MACHINE

Application filed May 16, 1923. Serial No. 639,266.

This invention relates to computing machines, and is herein illustrated as applied to an Underwood combined typewriting and computing or "bookkeeping" machine.

5 One feature of the present invention is the provision of many more dials in a totalizer than have heretofore been found practicable in a machine in which a number is set up on indexing devices preparatory to being run 10 into the totalizer.

One of the difficulties in devising a totalizer capable of computing in sextillions, for example, is that the ordinary transposition mechanism is adequate for only a small number 15 of decimal places. This is the mechanism which causes the typewriter carriage, as it proceeds from right to left, to select the denominations from left to right.

Another difficulty is the carry-over mechanism, which usually includes a shaft rotated 20 by the general operator, and having spurs thereon sufficient for driving the wheels of an ordinary size totalizer seriatim, but incapable of handling a totalizer of say double such 25 size.

A feature of the invention consists in the provision of means for effecting the carry-over in the register in stages, for example, by successive rotations of a carry-over-completing 30 shaft. Heretofore each register in said bookkeeping machine has been limited to about eleven computing bars, a set of dial-wheels, one for each of said bars, and an additional dial-wheel of higher order receiving 35 carryovers only from the highest order dial-wheel of said set. It will be evident that by effecting the carryovers in stages, use may be made of registers of greater capacity than the one to which reference has been made.

40 The transposition mechanism may be composed of a plurality of sets of transposition devices of forms now in use, thus avoiding redesigning of the transposition devices and serving other purposes to be brought out hereinafter. Each set forms a unit. These units have a transposed relation.

The transposition devices of each set are actuated by corresponding sets of jacks, and, in order to select denominations from the 50 highest to the lowest in order, it is necessary

to actuate seriatim from right to left the jacks of the left-hand set and then of the next set to the right. To this end, the forward ends of the jacks of the different sets are offset so that a denomination-selector may first 55 actuate the left-hand set of jacks seriatim, and, upon the completion of this operation, another selector may actuate seriatim the offset jacks of the second set. With this arrangement, it is evident that the effective 60 capacity of the register may be varied by throwing the left-hand selector or selectors out of operation.

To effect carryover for the sets of dial-wheels corresponding to the different sets of 65 computing bars and transposition devices, provision may be made of mechanism to effect carryover in the first set of dial-wheels and then in the second set, and, in case of a greater 70 number of sets, in the other sets successively. Heretofore, where a single set of computing bars and transposition devices has been used for each register the carryover has been completed by a single rotation of a shaft 75 actuated by the general operator only in its rearward movement. According to the present invention, the shaft for completing the carryover must be rotated once for each set of computing bars associated with the register. To this end, provision may be made of 80 suitable motion-multiplying mechanism between the general operator and the shaft for completing the carryover.

As herein disclosed, the shaft for completing the carryover is provided with disks having toothed portions or spurs to engage pinions forming part of the intermediate carry-over elements settable by the dial-wheels in passing from "9" to "0", the spurs being arranged helically. These disks are provided 85 with obstructions or stops, one for each carry-over pinion on the intermediate elements, so as to prevent overthrow when an intermediate element is actuated by a dial-wheel moving from "9" to "0". The corresponding 90 disks of the different sets may be of the same shape with one exception, namely, the carry-over-completing disk associated with the carry-over pinion of the lowest order in a set of higher order (left-hand set) differs 95 100

from the disk of lowest order of the set of lower order (right-hand set). This pinion may be advanced one step before the corresponding disk is brought to its initial position at the completion of a rotation of the carry-over-completing shaft, and to permit such advance movement of the pinion, a portion of the associated carry-over-completing disk has been cut out. Consequently, the 10 overthrow-preventing obstruction is eliminated from this disk, and to prevent overthrow of the corresponding carry-over pinion, provision is made of a pivotally-mounted pawl having at its front end an obstruction 15 normally lying in the path of the teeth of the carry-over pinion and at the other end a tooth or projection resting on the periphery of the associated carry-over-completing disk; the gap provided to permit rotation of the pinion being extended to a point such as to permit release of the pawl at the proper time.

Other features and advantages will hereinafter appear.

In the accompanying drawings,

25 Figure 1 is a diagrammatic side elevation, partly in section, showing the invention applied to an Underwood bookkeeping machine.

Figure 2 is a fragmentary front view, partly in section, showing the operating connection between the general operator and the carry-over-completing shaft.

30 Figure 3 is a top plan view of the computer, parts being omitted to show the underlying structure.

35 Figure 4 is a view, from the left, of the dial-wheels and carry-over mechanism, showing the carry-over-completing disk of the set of lowest order and the corresponding dial-wheel with its carry-over tooth in position to actuate the intermediate carry-over element in passing from "9" to "0".

40 Figure 5 is a view similar to Figure 4, showing the intermediate carry-over element advanced one step by the carry-over tooth of the dial-wheel and held against overthrow by the carry-over disk of lowest order.

45 Figure 6 is a view similar to Figure 5, showing the carry-over disk of highest order in the first set in engagement with the corresponding intermediate carry-over element, to carry-over from the dial-wheel of highest order of the first set to the dial-wheel of lowest order of the second set.

50 Figure 7 is a view showing the carry-over element after a partial rotation by the dial-wheel of the highest order of the lowest set, and the corresponding carry-over completing disk about to complete the carrying-over rotation, to the wheel of lowest order in the highest set.

55 Figure 8 is a view similar to Figure 7, but showing the disk of lowest order in the second set in position to permit the intermediate carryover to be set by the 12th dial, the

disk having a suitable cutout for this purpose.

60 Figure 9 is a view showing the carry-over-completing disk of lowest order in the first set in the position corresponding to that of the disk in Figure 8 and locking the corresponding carry-over pinion.

65 Figure 10 is a fragmentary front elevation, showing the left-hand denomination-selector on the point of releasing the jack of lowest denomination of the highest or left-hand set, and the right-hand selector on the point of engaging the jack of the highest denomination of the lowest or right-hand set of jacks.

70 Upon depression of numeral-keys 11 of the typewriter, key-levers 12 act through bell-crank 13 to swing type-bars 14 to print against a platen 15 mounted in a carriage 16. The carriage 16 is mounted upon front and rear rails 17 and 18, respectively, and is urged to the left by the usual spring-drum, not shown. To control the movement of the carriage 16, provision is made of a rack 19 connected with the carriage 16 and normally in mesh with a pinion 20 having the usual one-way connection with an escapement wheel 21, which, in turn, is controlled by fast and loose dogs 22 and 23, respectively. As each type-bar approaches its typing position, a heel 24 thereon engages a universal 75 frame 25, thereby shifting the loose dog 23 out of engagement with the escapement wheel 21, and the fast dog 22 into engagement therewith. Upon the return of the actuated type-bar to its normal position, the fast dog 22 will be withdrawn and the loose dog 23 brought into engagement with the escapement wheel 21, thereby permitting an advance movement of the escapement wheel 21 in the usual manner.

80 The numeral-keys 11, with the exception of the "0" key, have stems or pends 26 to depress arms 27 on rock-shafts 28 provided with arms 29 connected with linkages 30 to depress bars 31 for setting index-pins 32 on computation bars 33.

85 The pins 32 are normally out of alignment with the bars 31, but, as the carriage travels across the machine, a denomination-selector 34 is raised into effective position by a frusto-conical roll 35 thereon riding up on a lifting roller 36. Upon further movement of the carriage, a selector-dog 37 on the selector will engage and cam upwardly the front ends of a set of jacks 38, thereby rocking the jacks about a pivot 39 and depressing links 40 to rock bails 41 supported on a fulcrum-rod 41^a of a transposition device 42, thereby advancing seriatim the computation bars 33 of a set corresponding to the jacks 38, so as to bring the pins 32 into vertical alignment with the bars 31. When one of the computation bars 33 is so advanced, depression of a pin-setting bar 31 will set the correspond-

ing pin 32 on the selectively-advanced computation bar 33.

Upon completion of the indexing of a number on the computation bars 33 corresponding to the active jacks 38, the computation of the number so indexed may be effected by pulling forward a handle 43 and then returning it to its normal position. This handle is mounted upon the end of a shaft 44 having fixed thereon at each side of the computer a segment 45 meshing with an idle pinion 46, which, in turn, meshes with a rack 47 forming part of a general operator, indicated in general by 48. The forward movement of the handle 43 will effect forward movement of the general operator 48 and cause a cross-bar 49 thereon to engage the lower ends of the depressed pins 32 and advance the computation bars 33 distances corresponding to the numerical values of the digits indexed.

At their forward ends, the computation bars 33 are provided with racks 50 engaging with pinions 51 having one-way connections with dials 52, such that the forward movements of the computation bars 33 will advance said dials an extent corresponding to the forward pin-set movements of the corresponding computation bars 33, and, upon rearward movements of the computation bars 33, the pinions 51 will revolve idly with respect to the corresponding dials 52. Toothed wheels 53 are fixed to the different dials 52, and co-operate with detents 54 urged against them by springs 55, so that the dials will be held in proper position upon completion of the drive thereof and will be prevented from accidental movement during the rearward movement of the computation bars 33. During the rearward movement of the general operator, carryover between the dials will be effected by means to be described hereinafter.

The mechanism described so far may be in general similar to that disclosed in my Patent No. 1,370,360, dated March 1, 1921.

As herein disclosed, use is made of a register of substantially twice the usual capacity, and the usual transposed actuation of the computation bars 33 is effected by using two complete transposition sets or units side by side, as shown in Figure 3, each set being of sufficient capacity to control eleven computation bars. Obviously, the left-hand or highest transposition devices 56 must be actuated before the lower transposition devices 42 are actuated.

To operate the elements of the transposition device 56, use is made of a set of thrust links 40 corresponding to those used in connection with the transposition device 42 and of a set of jacks 59 similar to the jacks 38 but having their forward ends offset or elongated forwardly, as shown in Figure 1, to enable them to be operated independently of the jacks 38. Provision must also be made of an additional denomination-selector 60 having

thereon a selector-dog 61 to engage the forward ends of the jacks 59, the selectors 34 and 60 being so positioned that, as the selector 60 completes the actuation of the jacks 59, the selector 34 will be brought into operation on the jacks 38. Usually the length of a lifting roller, such as 36, is substantially the width of a set of jacks, but in the present case it is made of sufficient length to extend from the upper end of the set of jacks of highest order to the lower end of the set of jacks of lowest order, as shown in Figure 10.

Each dial 52 is provided with a carry-over tooth 62 so positioned that while the dial 52 is moving from "9" to "0" in each revolution, the tooth will engage one of the teeth of a pinion 63 and turn the pinion substantially one-ninth of a revolution to start the tens-carrying train of which the pinion forms a part. The pinion may be detained in the various positions to which it is shifted by means of a spring detent comprising a ball 64 mounted in a cylindrical opening 65 in a shaft or rod 66 on which the pinion 63 is loosely mounted, the ball 64 being pressed outwardly by a spring 67 so as to engage in openings 68 provided at suitable intervals in the pinion 63.

The pinion 63 forms part of an intermediate carry-over element which also includes a three-toothed pinion 69 to mesh with the toothed wheel 53 of the dial of next higher denomination. Each intermediate element, in completing the carryover, is turned altogether through one-third of a revolution, so that the three-toothed pinion 69 secured thereto will turn the toothed wheel 53 connected with the dial of next higher denomination through one-tenth of a revolution.

To complete the action of the carry-over trains which have been operatively set by carry-over teeth 62, provision is made of carry-over-completing means operable by the general operator during its return movement, and comprising a carry-over-completing element 70 to co-operate with each pinion 63. The carry-over-completing elements are mounted on a square portion of a shaft 71 rotatably supported by pins 72 projecting into openings in the ends thereof. Said pins 72 project inwardly through the inner ends of bosses 73 projecting inwardly from the sides of the computer-casing 74, and each of the pins 72 has an enlarged threaded portion 75 to screw into the corresponding boss, and a slotted head 76 for use in screwing the pin into and out of the boss. At its left end the shaft 71 is rounded to carry a sleeve 77, on which is fixed a pinion 78 to mesh with a gear 79, forming part of a rotatable part 80, comprising also a pinion 81 meshing with the left-hand rack 47 of the general operator. The gear and pinion are so proportioned that the pinion 78 is turned through two complete revolutions during a stroke of the general

operator in either direction. The rotatable member 80 is mounted on a pivot 82, passing outwardly therethrough and having a reduced end 83 threaded into a boss 84 projecting inwardly from the side of the computer-casing, the pivot being locked in position by means of a lock-nut 85 screwed on the outer end of said reduced portion 83.

Inasmuch as the shaft 71 is to be rotated only during the return stroke of the general operator, provision is made of a one-way connection between the sleeve 77 and the shaft 71, comprising a collar 86 fixed on the shaft 71, adjacent the enlarged inner end of the sleeve 77, by means of a screw 87, and carrying a pin 88 to engage in a notch 89 in said enlarged inner end of the sleeve 77.

The pin 88 is mounted in a cylindrical opening 90 in the collar 86 and has a reduced part 91, extending through an opening 92 of smaller diameter than the opening 90, and a button 93 at its outer end to limit its movement to the left (Figure 2) under the action of a spring 94. During the forward movement of the general operator, the pin 88 will be cammed to the right by the inclined surface 95 at one side of the notch 89, and the shaft will remain at rest. During the return movement of the general operator, the pin 88 will serve to connect the shaft 71 with the sleeve 77 to be moved therewith.

The carry-over-completing elements 70 may be in the form of disks having toothed portions or spurs 96 arranged helically in successive coils, the corresponding spurs of corresponding elements 70 of the different sets being in alignment. All of the elements 70 of the set of lowest order are provided with overthrow stops or shoulders 97, all of which are in alignment and are normally positioned (Figure 4) so as to project into wide gaps between the teeth of the pinions 63 which correspond to nine-toothed pinions with every third tooth omitted.

As illustrated in Figures 4 and 5, for the carry-over train of lowest order, the dial, in passing from "9" to "0", shifts the intermediate carry-over element to the position shown in Figure 5, with a tooth of the pinion 63 in engagement with the stop 97. When the shaft 71 is rotated, the stops 97 are withdrawn from their effective positions and the spurs 96 engage the teeth of the operatively-set pinions 63 and advance them two steps to complete for each the movement of one-third of a revolution.

Each element 70 of the first set has a circular dwell-portion 98 extending from the spur 96 to the stop 97 and engaging in the next wide gap between the teeth of the corresponding pinion 63, to lock the same as soon as the spur becomes disengaged therefrom. As indicated in Figures 4 and 6, the dwell-ports 98 of the elements 70 decrease progressively from that of the disk of lowest

order, shown in Figure 4, to that of highest order of the first set, shown in Figure 6. It will be seen that the carry-over mechanism for the first set of dial-wheels is, in many respects, similar to that disclosed in the patent 70 to Thornton, No. 1,228,148, dated May 29, 1917.

The elements 70 of the second set, or any higher set of elements 70, are, with the exception of the first element of the set, the same 75 as those of the first set. When the shaft 71 reaches the position shown in Figures 8 and 9, a carryover may be effected from the dial of highest order of one set to the dial of lowest order of the next set, and if this causes 80 the movement of the last-mentioned dial from "9" to "0", the corresponding pinion will be actuated one step. If, however, the element 70 of the lowest order in the highest set, Figure 8, were in the same position as the element 70 of lowest order in the first set shown in Figure 9, the pinion 63 would be locked against rotation and thus tie up the register.

It is desirable to prevent overthrow of 90 the pinion 63 associated with the element 70 having a cutout 99. To this end, provision is made of a pawl 100, pivotally mounted on a rod 101 supported at its ends in the end plates 102 of the register, and held 95 against movement along said rod by collars 103 on opposite sides thereof. The pawl 100 has a tooth 104 at its forward end to engage between the teeth on the pinion 63, and a laterally-projecting tooth 105 at its rear end 100 to co-operate with the dwell 98 on the corresponding member 70, the cutout 99 being of such length that, when the shaft 71 is turned from its normal position, shown in Figure 7, to bring the spur 96 thereon into engagement with the teeth of the pinion 63, the pawl 100 will ride off the end of the dwell-portion 98, thereby releasing the pinion 63. As soon as the spur 96 passes the tooth 105, the latter will again be engaged by the dwell-portion 98 and the pawl shifted into effective position. The inclined forward face 106 of the pawl 100 obviates any interference by the pawl 100 with the movement of the spur 96. 110

The spurs 96 and the carry-over-completing elements 70 of each set are spaced about 27 degrees apart around the shaft 71, so that the eleven spurs 96 of the first set of elements will extend through 297 degrees around the shaft 71. It will be seen that, if the helically-arranged spurs 96 were continued in this order around the shaft 71, the 13th spur would come where its overthrow-preventing obstruction or stop 97 should be, thereby making such an arrangement impossible. 115 By the present arrangement, provision is made of a gap of about 63 degrees between the highest spur of the first set and the lowest spur of the second set, thus providing, in connection with the cutout 99 in the first 120

element 70 of the second set, for carrying-over from the first set to the second set. Ample time will thus be given for such carryover before the second set of elements 70 of the carryover-completing means is brought into operation.

From the foregoing it will be understood that the register comprises an extraordinary number of dial-wheels arranged in denominational order; that there is provided a series of computing bars, one for each dial-wheel, said computing bars being divided into two groups; that for a pin-set machine of this character there is associated with the computing bars indexing mechanism to set up a number thereon; that the denomination-selecting mechanism is divided into two groups, the first group of lower order and the second group of higher order, each group comprising a set of transposition-devices; that there are provided two sets of jacks, one set for each set of transposition-devices; that there are provided two selectors on said carriage, one for each set of jacks to actuate said jacks; and that said selectors are arranged so that the jacks of the second group of denomination-selecting mechanism are actuated, first by one of the selectors, and that the other selector becomes subsequently effective to actuate the jacks of the first group of denomination-selecting mechanism to actuate the computing bars so as to set up on the computing bars a number comprising an extraordinary number of digits. It will further be understood that the register comprises a carry-over device having a plurality of carry-over elements arranged in more than one coil of a helix; and that the general operator drives the dial-wheels on its forward stroke and actuates on its return stroke the carry-over device through suitable means to rotate said carry-over device through more than one revolution to effect all of the carry-overs of the extraordinary number of dial-wheels from the lowest to the highest denominational order.

Variations may be resorted to within the scope of the invention, and portions of the improvements may be used without others.

Having thus described my invention, I claim:

1. In a computing machine, a series of denominational dials, a series of carry-over elements, each settable by a dial for actuating the dial of the next higher denomination, and a rotatable carry-over-completing device effective on said elements in successive rotations to effect carryovers between successive groups of dials.
2. In a computing machine, a series of denominational dials, a series of carry-over elements, each settable by a dial for actuating the dial of the next higher denomination, and a rotatable carry-over-completing device effective on said elements in successive rotations to effect carryovers between successive groups of dials.

tions to effect carryovers between successive groups of dials, and comprising carry-over-completing members having actuating spurs arranged in a plurality of helical coils.

3. In a computing machine, a series of 70 denominational dials, a series of carry-over elements, each settable by a dial for actuating the dial of the next higher denomination, and a rotatable carry-over-completing device effective on said elements in successive rotations 75 to effect carryovers between successive groups of dials, and comprising carry-over-completing members having actuating spurs arranged in a plurality of helical coils and aligned stops associated with all of said spurs, except 80 the first in the second helical coil, for preventing overthrow of said elements by said dials, the one overthrow stop being omitted to permit a carryover from the dial associated with the last spur of the first helical coil to the 85 dial associated with the first spur of the second helical coil.

4. In a computing machine, a series of 90 denominational dials, a series of carry-over elements, each settable by a dial for actuating the dial of the next higher denomination, and a rotatable carry-over-completing device effective on said elements in successive rotations 95 to effect carryovers between successive groups of dials, and comprising carry-over-completing disks having operating spurs arranged in helical coils, aligned overthrow stops for all but the one having the first spur in the second helical coil, and dwell surfaces extending from the spurs to the stops to engage said 100 carry-over elements after actuation by the spurs and lock them until said overthrow stops are brought to their normal positions.

5. In a computing machine, a series of 105 denominational dials, a series of carry-over elements, each settable by a dial for actuating the dial of the next higher denomination, and a rotatable carry-over-completing device effective on said elements in successive rotations to effect carryovers between successive groups 110 of dials, and comprising carry-over-completing disks having operating spurs arranged in helical coils, aligned overthrow stops for all but the one having the first spur in the second helical coil, dwell surfaces extending from the spurs to the stops to engage said carry-over elements after actuation by the spurs and lock them until said overthrow stops are brought to their normal positions, and an overthrow pawl to engage the carry-over element associated with the disk on which the stop is lacking.

6. In a computing machine, a series of 115 denominational dials, a series of carry-over elements, each settable by a dial for actuating the dial of the next higher denomination, and a rotatable carry-over-completing device effective on said elements in successive rotations to effect carryovers between successive groups of dials, and comprising carry-over-

completing disks having operating spurs arranged in helical coils, aligned overthrow stops for all but the one having the first spur in the second helical coil, dwell surfaces extending from the spurs to the stops to engage said carry-over elements after actuation by the spurs and lock them until said overthrow stops are brought to their normal positions, and an overthrow pawl to engage the carry-over element associated with the disk on which the stop is lacking, the last-mentioned disk having a circular dwell portion to engage the pawl and lock it in effective position until the disk is rotated to the position in which actuation of the carry-over element may be effected by the dial of next lower denomination.

7. In a computing machine, the combination with dials, each having a carry-over tooth, a member for effecting a carry-over from one of said dials to the dial of next higher denomination, comprising a pinion having teeth corresponding to a nine-toothed pinion but with every third tooth omitted, said carry-over member being advanced one step by the carry-over tooth of the dial of next lower denomination when the dial passes from "9" to "0"; means to lock the carry-over member against overthrow by the next lower dial, comprising a pawl having a tooth projecting into one of the wide gaps on the periphery of the pinion; and a carry-over-completing disk having a spur to engage a tooth of the pinion after the pinion has been advanced one step by the next lower dial, and advance the pinion sufficiently to complete the carry-over, said disk having a circular dwell at its periphery to engage in one of the wide gaps in the pinion to lock the same to prevent overthrow after the spur has acted on the pinion, and serving also to engage one end of the pawl to lock it in engagement with the pinion, the disk being cut away so that when the spur is moved into engagement with the pinion the pawl will be released.

8. In a machine of the class described, a rotary device comprising a plurality of carry-over-completing spurs arranged in successive coils of a helix.

9. In a machine of the class described, a rotary device comprising a plurality of carry-over-completing spurs arranged in successive coils of a helix, a series of locking dwells associated with said spurs, respectively, and an overthrow-preventing device controlled by each locking dwell associated with the first spur in a helical coil of higher order than the first.

10. In a machine of the class described, a rotary device comprising a plurality of carry-over-completing spurs arranged in successive coils of a helix, the angular interval between the last spur of one coil and the first spur of the next coil being greater

than the uniform intervals between successive spurs in any of the coils, to enable a carry-over to be effected from the dial of highest order of one set to the dial of lowest order of the next set before effecting the next carry-over action on the second set.

11. In a machine of the class described, a rotary device comprising a plurality of carry-over-completing spurs arranged in successive coils of a helix, a series of locking dwells associated with said spurs, respectively, a series of overthrow-stops associated with said spurs except the first spur in each helical coil of higher order than the first, and an overthrow-stop-device controlled by said rotary device to be effective and ineffective in accordance with the rotary position of the last-mentioned spur.

12. In a machine of the class described, a rotary device comprising a plurality of carry-over-completing spurs arranged in successive coils of a helix, and a series of locking dwells associated with said spurs, respectively; the angular interval between the last spur of one coil and the first spur of the next coil being greater than the uniform intervals between successive spurs in any of the coils, to enable a carry-over to be effected from the dial of highest order of one set to the dial of lowest order of the next set before effecting the next carry-over action on the second set.

13. In a machine of the class described, a register comprising a plurality of dials, a carry-over member settable by one of said dials to effect a carry-over to the dial of next higher denomination, a carry-over-completing member to complete the carry-over movement of said carry-over member, and a pawl controlled by said carry-over-completing member to prevent overthrow of the carry-over member by the dial of next lower denomination.

14. In a machine of the class described, a register comprising a plurality of dials, a rotatable carry-over member settable by one of said dials to effect a carry-over to the dial of next higher denomination, a rotatable carry-over-completing member to complete the carry-over movement of said carry-over member and to lock it against overthrow, and means controlled by said carry-over-completing member for preventing overthrow of the carry-over member by the dial of next lower denomination, the overthrow-preventing means being maintained in effective position until the carry-over-completing member is advanced to a position to actuate the carry-over member.

15. In a computing machine, the combination of a series of carry-over pinions, two sets of carry-over completing sectors arranged in successive coils of a helix, locking dwells associated with said sectors, and overthrow-prevention devices associated with all of said

dwells, the overthrow-prevention devices of all of said dwells except the one of lowest order in the second set being formed on said dwells, the overthrow-prevention device associated with said dwell of lowest order being separately supported and controlled by its associated dwell.

16. In a computing machine, the combination of two adjacent dial-wheels arranged in denominational order, a carry-over pinion settable by the dial-wheel of lower denominational order, a revolute element to actuate said pinion after it has been set to revolve the dial-wheel of higher order through one digit position, and means comprising a pivoted element to be engaged by said revolute element to prevent possible overthrow of the carry-over pinion when said pinion is actuated by the dial-wheel.

17. In a computing machine, the combination of two adjacent dial-wheels arranged in denominational order, a carry-over pinion settable by the dial-wheel of lower denominational order, a revolute element comprising a shaft and a sector on said shaft to engage said pinion, after it has been set, and further actuate it to revolve the dial-wheel of higher order through one digit position, a disk on said shaft, and means comprising a pivoted element to be engaged by said disk to prevent overthrow of the carry-over pinion when said pinion is actuated by the dial-wheel.

18. In a computing machine, the combination of two adjacent dial-wheels arranged in denominational order, a carry-over pinion settable by the dial-wheel of lower denominational order, a revolute element comprising a shaft and a sector on said shaft to engage said pinion, after it has been set, and further actuate it to revolve the dial-wheel of higher order through one digit position, a disk on said shaft, said disk having a cutout and a dwell on its periphery, and means comprising a pivoted element engaging said dwell to prevent overthrow of the carry-over pinion when said pinion is actuated by a dial-wheel, said pivoted element being capable of engaging in the cutout of said disk to render said pivoted element ineffective, so that the carry-over pinion may be rotated freely by said sector.

19. In a register for a machine of the class described, the combination of a rotary device comprising two groups of carry-over completing elements, said groups arranged in successive coils of a helix, the first group containing the overthrow completing elements of lower denominational order, the second group containing those of higher denominational order, overthrow-prevention devices associated with all of the carry-over completing elements except the one associated with the element of lowest order in the second group, said carry-over completing elements being connected to said overthrow-prevention

devices, and a separate overthrow-prevention device associated with said element of lowest order, the last-named overthrow-prevention device being individually supported and controlled by said lowest order element.

20. In a computing machine, the combination of carry-over pinions, a shaft, a plurality of carry-over completing disks to co-operate with said pinions, said disks comprising two groups on said shaft, the first group containing carry-over completing disks of lower denominational order, the second group containing those of higher denominational order, said disks having teeth thereon arranged in successive coils of a helix, all of the carry-over completing disks except the one of lowest order of the second set having an overthrow-prevention stop thereon, said stops to co-operate with the carry-over pinions, and a separate support for the overthrow-prevention stop associated with said lowest order disk.

21. In a combined typewriting and computing machine of the character described, the combination of a register including a great multiplicity of dial-wheels, a carry-over device comprising a plurality of carry-over elements arranged in more than one coil of a helix, a series of dial-driving elements, indexing devices on said dial-driving elements, mechanism to enable a number to be set up on said dial-driving elements by said indexing devices, a general operator to actuate the dial-driving elements after the number has been set up, and means actuated by the general operator to subsequently revolve said carry-over device through more than one revolution to effect all of the carry-overs for the dial-wheels from lowest to highest denominational order.

22. In a combined typewriting and computing machine of the class described, having a register that includes a great multiplicity of dials, denominational devices having index-devices in which digits may be indexed and a general operator to run numbers so indexed into the register, a set of intermediate carry-over devices, said set of intermediate carry-over devices forming a helical row of a plurality of convolutions, each carry-over device settable by a dial to actuate the next higher dial, a multiple-revolution rotary carry-over-completing device, and a one-way connection between the carry-over-completing device and said general operator to operate the carry-over-completing device during a movement of the general operator, to complete the carry-over from each dial-wheel to the next succeeding one, said one-way connection including movement-multiplying means to effect a plurality of revolutions of the set of carry-over-completing devices to complete the carry-overs for all the dial-wheels.

23. In a register for a machine of the class described, the combination of a rotary device comprising two groups of carry-over completing elements, said groups arranged in successive coils of a helix, the first group containing the overthrow completing elements of lower denominational order, the second group containing those of higher denominational order, overthrow-prevention devices associated with all of the carry-over completing elements except the one associated with the element of lowest order in the second group, said carry-over completing elements being connected to said overthrow-prevention
